UNITED STATES PATENT OFFICE.

HERMAN BURGI, OF SPRINGFIELD, MASSACHUSETTS, ASSIGNOR OF ONE-HALF TO CHARLES HENRY TENNEY, OF SPRINGFIELD, MASSACHUSETTS.

CONTINUOUS PROCESS OF MAKING COKE AND ILLUMINATING GAS.

Application filed February 14, 1922. Serial No. 536,463.

To all whom it may concern:

Be it known that I, HERMAN BURGI, a citizen of the United States, and residing at Springfield, Hampden County, State of Massachusetts, have invented certain new and useful Improvements in Continuous Processes of Making Coke and Illuminating Gas, of which the following is a specification.

10 My invention relates to an improved process of making coke and illuminating gas and has reference more particularly to what is generally known as a continuous process wherein coal is continuously fed into the 15 upper end of a retort and moves downwardly through the retort to the lower end thereof where the residue is withdrawn, heat being applied to the coal during its travel through the retort.

20 In the continuous process now in commercial use for making illuminating gas, the heating of the contents of the retort is done from the outside of the retort, the heat generally being obtained by burning a mixture 25 of a suitable gas, such as carbon monoxide and preheated air near the external surface of the walls of the retort. The heat thus secured through combustion must penetrate the walls of the retort in order to heat the 30 coal and liberate the gases therefrom.

By my improved process, I heat the coal in the retort by means of heat generated inside the retort itself. The heat is generated by forming a combustion zone at the lower 35 end of the retort. This is accomplished by burning a portion only of the coke produced so that the heat generated and hot gases produced by such combustion will serve to drive off the volatile constituents of the entire 40 mass of coal as it descends through the retort. In carrying out my process preheated air in proper quantity is injected into the retort at the lower end thereof, which as stated 45 combines with a portion only of the hot coke to produce a combustion zone at the lower end of the retort, forming carbon dioxide, which evolves sufficient heat to enable it, while passing upwardly in the retort, to carbonize all of the descending coal or in other 50 words to drive off the volatile constituents of the coal. The unburned remainder of the coke passes downwardly to the lower end of the retort where it is withdrawn. Since only a small portion of the coke is consumed, 55 to supply the necessary heat, my process re-

sults in the formation of a large percentage of coke and this is one of the important features of my process. As the carbon dioxide formed at the lower end of the retort passes upwardly through the hot coke, it reacts 60 therewith to form carbon monoxide, thus reducing the non-combustible constituents of the final gas produced. To assist the operation, I also inject steam into the lower end of the retort, which serves to prevent clinkering and to keep down the temperature at the point where carbon dioxide is formed. A portion of the steam coming in contact with the hot coke is converted into water gas which with the excess steam passes upwardly and assists in rapidly removing the volatile products of carbonization from the reacting zone. This rapid removal serves to preserve valuable constituents of the gas 70 from decomposition by decreasing the time they are in contact with the hot walls of the retort. The amount of heat generated at the lower end of the retort is so regulated that the carbonization of the coal is carried only to such a point as to preserve the tar, ammonia, and the like. The process is operated so that the pressure inside the retort is substantially the same as the atmospheric 80 pressure.

Any suitable apparatus may be employed for carrying out my process. In the drawings accompanying this specification and forming a part thereof, I have shown two vertical retorts 1 and 2 which are provided on their upper ends with the usual coal feeding apparatus 3, the latter being of any suitable construction. The lower ends of the retorts are provided with any suitable mechanism 4, 4, for extracting the residues. In the lower end of each retort slots or openings 9 are provided through which preheated air from any suitable source may be injected into the retorts, the air being furnished in quantities sufficient to burn up enough of the coke to provide the necessary heat to carbonize all of the coal. Below the openings 9 each of the retorts is provided with openings 10 through which steam from any suitable source may be supplied to the inside of the retorts, the steam, as heretofore stated, being partially converted into water gas which with the excess steam and products of combustion pass upwardly through the descending coal and cause rapid removal 100 of the volatile products of carbonization 105 110

from the reacting zone resulting in a tendency to protect the ammonia, tar, methane and illuminants from reaching a state of equilibrium which would be fatal to their 5 preservation.

It has been found that the unburned portion of the coke after passing the zone of combustion is practically free from volatile constituents and such coke is passed downwardly from this zone preferably out of contact with air or other gas and is finally withdrawn from the retort. At an intermediate point in each of the retorts, there is arranged an exit pipe 7 for the escape 10 of the gas produced, this pipe being positioned at a point where the temperature is such as to permanently fix and render stable the constituents of the gas produced as set forth in my prior Patent No. 1,095,806. For 15 the purpose of supplying enriching oils to the coal to improve the illuminating and heating value of the gas, each of the retorts is provided with a pipe 8, which pipes extend downwardly from the top of the retorts to a point in the region of the exit 20 pipes 7.

It will be understood that the apparatus thus described is more or less diagrammatic and that the proportions shown are not to 25 be taken as indicative of the proportions which would necessarily be used in actual practice and, therefore, the drawings are to be considered as merely illustrative of the principles of the invention.

The continuous process as thus described 30 possesses numerous advantages over those now in use for making coke and illuminating gas. The coal is heated directly by contact with the hot gases formed by the combustion of a portion of the coke in the retort and loss or waste due to the transmission of heat through the walls of the retort is obviated. Furthermore, where the heat 35 is applied to the exterior of the retort it is difficult to properly heat and carbonize the coal at the inner part of the retort and this can be done only by heating the retort and outer layers of coal to an excessively high temperature. This results in further loss 40 of heat. In my process, therefore, a lower degree of heat can be used which is applied directly to the coal in the retort. This results in economy of heat. Also by using a lower degree of heat by burning a part of 45 the coke with preheated air, a much higher percentage of ammonia, tar, methane, light and heavy oils, and the like, is obtained since decomposition and loss of volatile products is avoided. The result is an increase 50 in the volume of gas produced per unit of

coal carbonized and a decrease in the amount of fuel required to produce the carbonization. At the same time my process results in the production of a comparatively large amount of coke because only a small portion 55 is consumed in the heating operation. Also the amount of non-combustible products will be small due to the reaction of the carbon dioxide formed with the incandescent coke to form carbon monoxide. In addition to 60 the foregoing, my process has the advantage that no apparatus for supplying heat to the outside of the retorts is necessary and hence expensive installations of generators, or producers, flue systems, chimneys, or the like are avoided. A plant using my process has greater capacity for gas production, thus reducing the capital charge and the 65 ease and flexibility of control reduces the amount of labor necessary. 80

What I claim as my invention and desire to secure by Letters Patent is:

The herein described process of making coke and illuminating gas which consists in continuously passing coal in a solid body 85 downwardly through a retort which is externally unheated and provided with an unrestricted chamber from the top to the bottom thereof, maintaining a limited zone of combustion in said retort above the bottom 90 thereof by burning a portion only of the coke formed therein to generate heat to carbonize the descending coal, injecting pre-heated air into the retort above its lower end to supply oxygen for the combustion of 95 said portion of the coke being burned, injecting steam into the retort below the point at which the air is injected and at a point where the coke is at sufficiently high temperature to react with the steam, passing 100 the products of combustion and gas formed in the lower part of the retort upwardly through the descending body of the coal to heat and carbonize the same and drive off its volatile constituents, passing the remainder 105 of the coke downwardly in a unitary column beyond said combustion zone and beyond the points at which the air and steam are injected, while maintaining the same out of further contact with air or gas, withdrawing from the upper part of the retort 110 the gases and volatile products produced and continuously withdrawing the remaining coke from the lower end of the retort below the point at which the steam is injected therein. 115

In testimony whereof I hereunto affix my signature.

HERMAN BURGI.
